UNITED STATES PATENT OFFICE.

ANDREW LOCHHEAD, OF OAKLAND, CALIFORNIA.

NAIL-HOLDING ATTACHMENT FOR HAMMERS.

Application filed March 7, 1927. Serial No. 173,389.

My invention relates to improvements in nail holding attachments for hammers, adapted to be secured to the conventional claw-hammers, although also attachable to hatchets or like hand tools; and the primary object of the invention is the provision of a plate pivotally secured to the handle of the hammer and having nail engaging jaws adapted to bear against one side of the head of the hammer and cooperating therewith for temporarily holding a nail therebetween for facilitating in projecting the nail in a support, particularly in a support ordinarily out of the reach of the hand of the workman.

With the foregoing and further objects and purposes in view which will appear as the description proceeds, my invention resides in the combination and arrangements of parts and the details of construction hereinafter described and claimed, it being understood that changes in the precise embodiment of the invention herein disclosed can be made within the scope of what is claimed without departing from the spirit of the invention.

In the accompanying drawings—

Figure 1 is a side elevation of a hammer with one of my improved nail holding attachments secured thereto, and a nail disposed between the jaws of the attachment, with the head of the nail bearing against one side of the head of the hammer;

Figure 2 is a view on line 2'-2' of Fig. 1;

Figure 3 is a longitudinal sectional view on line 3'-3' of Fig. 1;

Figure 4 is an end view of the hammer, a cross sectional view of the attachment approximately on line 4'-4', Fig. 1, and a nail held by the attachment and projected a distance in a support.

Figure 5 is a side view of a hammer with a portion of the handle broken away, and one of the present attachments secured thereto, disposed in relative reverse order;

Figure 6 is a side or face view of the attachment plate removed from the hammer; and

Figure 7 is an enlarged, front end view of the attachment plate.

Referring to the drawings in detail, throughout which like reference characters designate like parts:

The numeral 1 designates the handle, and 2 the head, of a hammer, which has the usual driving face 3 and nail-pulling claws 4.

To one side of the handle 1, adjacent the head 2, is secured a screw 5, which pivotally

supports the plate 6 by passing through an opening 7 formed in the bottom of a concavo-convex indentation 8 intermediate the outer end 9 and inner end 10 of the plate.

The outer end 9 of the plate 6 is formed with a V-shaped slot 11, the edges of which are struck outwardly, thereby forming a pair of opposed nail-engaging jaws 12, 13, having outwardly projecting flanges 14, 15, extending substantially the length of said jaws.

The inner end 10 of the plate 6 is provided with an outwardly struck locking indentation 16 adapted to engage and cooperate with the oval head 17 of a pin 18 driven in the handle 1 at a distance from the screw 5, for normally frictionally holding the plate 6 in fixed relation to the hammer.

The plate 6 is preferably stamped from sheet metal sufficiently resilient so that when the screw 5, extending through the opening 7, is driven a proper distance in the handle 1, both the outer end 9 and the inner end 10 will be spring-pressed against the head 2 and handle 1, respectively, when the plate is disposed in operative position relative to the hammer as best illustrated in Figs. 1, 2 and 3. In this position the indentation 16 engages the head 17 and cooperates therewith to normally prevent rotation of the plate on the screw 5, but rotatable about the axis of said screw, in a plane substantially parallel with the handle 1, when the inner end 10 is operatively forcibly disengaged from the head 17 by the workman.

In Fig. 5 the plate 6 is shown disposed in longitudinally reversed position relative to the hammer, in which position the jaws 12, 13, are adapted to engage the head 17 (see Fig. 5), thereby normally frictionally holding the plate against rotation on the screw 5.

The purpose of the present invention is to provide means cooperable with a hammer or the like, whereby any one of a variety of ordinary nails may be temporarily held by the hammer for projecting the nail a distance in a support out of the normal reach of the operator, preparatory to the final driving of said nail by impinging it with the face of the hammer; and to operate the invention for said purpose, the head of the nail is forced between the jaws 12, 13, and the head of the hammer, with the shank of the nail disposed to project out between the flanges 14, 15, at a distance therebetween inwardly from their outer ends as far as the shank will normally go (see Figs. 1 to 4), the free end of the han-

dle 1 is then grasped by the operator and the hammer swung in the proper direction to cause the point of the nail to engage and penetrate the support a sufficient distance to hold the nail sufficiently steady to permit the withdrawal of the hammer therefrom, which is accomplished by simply drawing the hammer away from the nail in a direction towards the free end of the handle 1, thereby causing the head of the nail to slide out from between the jaws 12, 13, and the head of the hammer, and the shank to pass out of the free end of the slot 11. The nail may thereafter be driven further forward in the support by engaging it with the face of the hammer in the usual manner of driving nails.

The plate 6 is rotatably mounted on the screw 5, so that its opposed ends may be conveniently relatively reversed, to permit the head of the hammer to be temporarily freed from the jaws 12, 13, and the outwardly projecting flanges 14, 15, when it is desired to employ the hammer only for driving nails in the ordinary manner.

25 The numeral 19 designates the shank, and the numeral 20, the head of the nail, while 21 designates the support.

Having described my invention, what I claim and desire to secure by Letters Patent, 30 is:

1. In means of the character described, an elongated plate having a concavo-convex indentation formed in its mid-part, a screw projecting through said indentation for rotatably securing said plate to the handle of a hammer, a projection on said handle spaced from said screw engageable with one end of said plate for normally preventing rotation

of said plate on said screw, the opposite end of said plate being bifurcated to form a V- 40 shaped slot, said last named end adapted to cooperate with the head of said hammer for removably confining a nail in said slot.

2. The combination with a hammer, of a plate having its midpart pivotally secured to 45 the handle of said hammer whereby said plate may be rotated for reversing it longitudinally, an indentation on one end of said plate adapted to frictionally engage a projection on said handle for normally preventing rotation of said plate for reversing it longitudinally, the opposite end of said plate normally disposed along one side of the head of the hammer for cooperating therewith for binding the head of a nail against said first named 50 head for holding the nail by the hammer preparatory to driving it in a support.

3. In means of the character described, a plate having its midpart pivotally secured to one side of the handle of a hammer adjacent 55 the head of the latter, whereby said plate may be rotated 360 degrees in a plane substantially parallel with said handle, opposed ends of said plate spring-pressing against said head and said handle when said plate is disposed in substantially longitudinal parallelism with said handle, one end of said plate adapted for operatively engaging and holding a nail against said head, and the opposite end thereof adapted to engage means on said handle for normally holding said plate against rotation.

In testimony of the foregoing being my own, I have hereunto affixed my signature this 23rd day of February, 1927.

ANDREW LOCHHEAD.
